UNITED STATES PATENT OFFICE

153,881

DESIGN FOR A RADIO RECEIVER

George H. Kress, Vestal, N. Y., assignor to International Business Machines Corporation, New York, N. Y., a corporation of New York

Application July 23, 1947, Serial No. 140,462

Term of patent 14 years

(Cl. D56—4)

To all whom it may concern:

Be it known that I, George H. Kress, a citizen of the United States, residing at Vestal, in the county of Broome and State of New York, have invented a new, original, and ornamental Design for a Radio Receiver, of which the following is a specification, reference being had to the accompanying drawing, forming part thereof.

Fig. 1 is a front elevation of a radio receiver, showing my new design.

Fig. 2 is a side elevation of the same.

Fig. 3 is a plan view of the same.

Fig. 4 is a perspective view of the same.

The back side of the receiver is plain and without ornament.

The fragmentary showing of straps in dot and dash lines in Figs. 1 and 4 is purely for illustrative purposes.

I claim:

The ornamental design for a radio receiver, as shown and described.

GEORGE H. KRESS.
